United States Patent Office.

AUGUSTUS H. CLEMENT, OF SUNBURY, PENNSYLVANIA.

Letters Patent No. 69,969, dated October 22, 1867.

IMPROVED WASHING MACHINE.

The Schedule referred to in these Letters Patent and making part of the same.

TO WHOM IT MAY CONCERN:

Be it known that I, AUGUSTUS H. CLEMENT, of the borough of Sunbury, in the county of Northumberland, and State of Pennsylvania, have invented a new and useful machine for washing clothing, any cloth or woollen fabric, styled a Double-Acting Washing Machine; and I do hereby declare that the following is a full, clear, and exact description of the construction and operation of the same, reference being had to the annexed drawings, making part of this specification, and to the letters of reference marked thereon, in which—

Figure 1 is a vertical section, and

Figure 2 a horizontal section, taken at $x x$, fig. 1.

I construct my washing machine in the form of a box. At a point equidistant from both ends of the box I insert a straight or curved lever, A, on pivots a . To the bottom of the lever I attach a board, B, perforated with holes or a rack. At each end of the box I insert a perforated board or rack, C, in one of three or more grooves, b , in the sides of the box, at a radius with the centre or pivot in the lever, which can be changed nearer or further distant from the centre to suit either the amount of water desired to be used or the quantity of clothes to be washed; and with the racks or perforated slides at each end, arranged in a radius with the centre or pivot, an equal pressure of the clothes between them and the lever is at all times secured. I construct the box with a double bottom, the inner one, D, of which is constructed in a half circle or curve, using the lower end of the lever as a radius, and is perforated to enable the water, when the clothes are pressed at one end of the machine, to pass back to the other end and loosen up the clothes already pressed. The pivots of the lever rest on two half circular pieces of wood, E, fitted in the sides of the machine so as to press upon and secure the perforated boards or racks in the grooves at each end of the machine. These pieces of wood can be easily removed and replaced in changing the racks or perforated boards from one groove to the other.

With a machine so constructed clothes can be placed at each end of the machine, on both sides of the lever, and while they are being washed at one end the water, rushing back through the false or circular bottom, and being agitated by the action of the lever, loosens up and rinses the clothes at the other end of the machine, and prepares them for another application of the lever.

What I claim as my invention, and desire to secure by Letters Patent, is—

The combination of the perforated bottom D and perforated slides C, in radial grooves b , boards E, and beater A B, substantially as described.

AUGUSTUS H. CLEMENT.
